UNITED STATES PATENT OFFICE.

FRANCIS HARRISON, OF LONDON, ENGLAND, ASSIGNOR TO THE ALADDIN RENEW ELECTRIC LAMP CORPORATION LIMITED, OF LONDON, ENGLAND.

MANUFACTURE OF INCANDESCENT ELECTRIC LAMPS.

1,416,197.

Specification of Letters Patent.

Patented May 16, 1922.

No Drawing.

Application filed July 8, 1919. Serial No. 309,335.

To all whom it may concern:

Be it known that I, FRANCIS HARRISON, a subject of the King of England, residing at London, England, have invented certain new and useful Improvements in the Manufacture of Incandescent Electric Lamps, of which the following is a specification.

This invention relates to incandescent electric lamps, its object being to provide a simple, inexpensive and rapid method of repairing a lamp whose filament has been broken, or which has otherwise become unserviceable.

The commonest type of metal filament in incandescent lamp at present in use is the drawn wire lamp containing a central glass stem with two leading-in wires, and several stiff or slender supporting hooks projecting from the foot, and several slender flexible molybdenum supporting hooks projecting from a glass knob at the free end of the central glass stem, and it is to the repair or renewal of this type of lamp that this invention relates.

It has already been proposed to wind a metal filament on a mandrel so as to form a fine helix or coil of very small diameter, and to mount the resulting filament in an electric lamp so that it is unnecessary to support at intermediate points filaments of such a length as those usually employed. I have found by experiment that a tubular coil of wire of the required dimensions is particularly suitable for use in the repair or renewal of unserviceable lamps of the type above referred to. The tubular coiled filament which I employ is prepared by winding a straight tungsten filament on to a stretched wire mandrel of diameter not more than ten times, and preferably about four times, the thickness of the filament wire.

According to this invention the process of repairing or renewing an unserviceable incandescent electric lamp of the type described comprises the following steps;

(a) making a small opening at the pip end of the bulb and flaring the edge of the opening by the use of a blow-pipe flame;

(b) removing old or broken filaments from the lamp and cleaning the interior, if necessary;

(c) preparing a coiled tungsten filament by winding a tungsten filament of the required total length on to a stretched mandrel of the dimensions specified;

(d) stretching the coil until the length of the coil is that required for insertion in the lamp;

(e) attaching two spring clips, as illustrated in Figure 3 of United States Patent No. 1,247,956 to the leading-in wires projecting from the foot, one clip carrying one end of the filament gripped in it;

(f) winding the coiled filament over one or more of the permanent supporting hooks in the lamp, and inserting the other end of the coiled filament between the turns of the other spring clip;

(g) fusing a glass tube to the edge of the opening in the bulb, and exhausting and sealing the lamp.

In the methods at present in use for renewing incandescent lamps of the type described for example in the British Patent No. 114464, a number of steps are involved including the preparation of a support for temporary stiff lower hooks, the attachment of this support to the central glass stem, the winding of the filament on to the temporary bottom hooks, the setting of the filament, the unshipping of the filament from the temporary hooks on to the permanent slender hooks, and the removal of the temporary support. It will be seen that the process constituting the present invention dispenses with all these steps.

One method of carrying out this invention is now described by way of example and as applied to the repair of an incandescent lamp of the ordinary type whose filament has been broken. A lamp, the filament of which was of the ordinary straight uncoiled wire arranged in zig-zag formation, but whose filament has become broken is taken and an opening made in the pip end in the known manner, such for example as is employed in the method of United States Patent No. 1,247,956.

Tungsten wire of the same diameter as that of the original broken filament, and a length about 10% greater than that of the original filament is taken and coiled into a tubular coil whose diameter is six times that of the wire. The coiling is carried out cold and direct upon a stretched wire mandrel of the desired diameter. To facilitate its removal from the mandrel, the latter may be lubricated with graphite, or the coil may be wound slightly open, and be closed upon itself during withdrawal from the mandrel.

In practice the stretched wire mandrel is composed of a drawn tungsten wire, and as a coating of graphite has been used on the wire during the drawing operation, the required lubrication of the surface is thereby furnished. The wire mandrel, being held in a lathe or wire-winding machine, is rotated on its own axis while the tungsten wire for the filament is wound on to it. The coiled filament thus prepared is obviously of much shorter length than the length occupied by the original straight-wire filament. This closely wound coil is conveniently stretched until the length of the coil is that required for insertion in the lamp.

The filament having been thus prepared and the bulb of the lamp having been subjected to the usual preliminary processes which form no part of this invention, the filament is slung between the leading-in wires of the lamp and one or more of the permanent hooks, but owing to its relatively short length it only occupies a small proportion of the said hooks. Its extreme flexibility enables it to be wound direct on to the permanent lower hooks, which are usually of molybdenum, thus avoiding the necessity heretofore regarded as inevitable, of employing stiff temporary hooks, or a former, for the operation of setting the filament. The strength and physical formation of the filament, moreover, are such that it can hang in loops of the usual length supported like an ordinary zig-zag filament and be properly incandesced, without sagging away from the usual lower hooks. An incidental advantage arises from the fact that the coiled filament gives a better distribution of light and particularly in a downward direction when the lamp is hanging by its cap so that the useful candle-power of the lamp is greater than it was with the original filament. Furthermore, the increased length of wire employed, namely about 10% greater than that of the original filament, affords a slight increase in the candle-power as compared with the lamp with its original filament.

It is to be understood that the precise relation of the diameter of the coil to the thickness of the wire may be varied provided always that the physical formation obtained is such that the filament can be supported in the manner of an ordinary zig-zag filament without sagging away from its supports in use, but the following dimensions have been found by experiment to be successful:—

	Diameter of filament.	Internal diameter of spiral.
60	.018 m.m. to .027 m.m.	.05 m.m.
	.028 m.m. to .040 m.m.	.08 m.m.
	.041 m.m. to .120 m.m.	.13 m.m.

A further advantage arising from a fila-

ment having the proportions provided by this invention is that it enables a much greater length of wire to be inserted in a given lamp than can be employed as a straight-wire zig-zag filament. This provides a ready means for repairing a lamp originally constructed for one voltage, in such a way as to be employed upon a higher voltage; indeed it has been found that a lamp originally wound for sixteen volts can be repaired with a filament according to the present invention so as to be used upon a 100 volt circuit. In carrying such a change into effect the requisite length of wire for the higher voltage is prepared in coiled form and the length of the coil is then simply and readily adjusted by stretching it so that it shall correspond with a convenient number of zig-zag loops to extend from one leading-in wire to another.

It may occur in many cases that some of the original supporting hooks of the lamp may not be required for the support of the coiled filament. It is, of course, a simple matter to nip these extra supports off during the repair, but I prefer to leave the extra supports as spares to be utilized if the lamp is renewed again, or in case that a supporting wire breaks during repair.

What I claim as my invention and desire to secure by Letters Patent is:—

1. The method of renewing metal filament lamps having permanent supporting hooks arranged therein in independent series located in different planes, comprising making an opening in the lamp bulb, removing the old filament therethrough and forming a new filament of a series of coils, and applying said new filament to any desired number of said hooks by stretching same to the desired length, substantially as described.

2. The method of renewing metal filament lamps having permanent supporting hooks therein, comprising making an opening in the lamp bulb, removing the old filament through said opening, forming a new filament of a continuous series of coils, and applying said new filament to any desired number of said hooks by stretching the same to the desired length, substantially as described.

3. The method of renewing metal filament lamps having permanent supporting hooks therein, comprising making an opening in the lamp bulb, removing the old filament through said opening, forming a coiled filament whereof the diameter of its turns is not more than ten times the diameter of the wire from which it is formed, and applying said coiled filament to any desired number of said hooks by stretching the same to the desired length, substantially as described.

In testimony whereof I affix my signature.

FRANCIS HARRISON.
